UNITED STATES PATENT OFFICE

JOHN T. RAMSDEN, OF PHILADELPHIA, PENNSYLVANIA, ASSIGNOR TO THE TABOR MANUFACTURING COMPANY, OF PHILADELPHIA, PENNSYLVANIA, A CORPORATION OF PENNSYLVANIA

SHOCKLESS SHAKE-OUT BAIL FOR MOLDS

Application filed May 22, 1928. Serial No. 279,795.

The present invention relates to improvements in shake-out bails used in connection with multiple molding machines for shaking sand out of the stack of molds or flasks after 5 the castings have been poured. One objection to shake-out bails with which I am familiar is that they may not be suspended from an overhead crane because the vibration crystallizes the crane hooks and chains.

10 The principal object of the present invention is to provide a shockless shake-out bail in the sense that no objectionable vibrations set up by the vibrator employed to shake out the sand are transmitted to the yoke so that 15 the yoke can be suspended from an overhead crane or the like. Another object of the invention is to provide a convenient and reliable shake-out bail of the character indicated.

20 Other objects of the invention will appear from the following description, and the invention, generally stated, may be said to comprise a shake-out bail for a stack of flasks including a yoke having suspension means, 25 tension rods freely slideable through the yoke and having lugs, vibrators on the rods, springs between the lugs and yoke for supporting the rods and opposing transmission of vibration to the yoke, and feet at the ends of the rods 30 for engaging the bottom flask.

The invention also comprises the improvements to be presently described and finally claimed.

In the following description reference will 35 be made to the accompanying drawings forming part hereof, illustrating a shake-out bail embodying features of the invention, and in which

40 Figure 1 is a front elevational view of a shake-out bail embodying features of the invention and showing a stack of flasks or molds supported thereby.

Fig. 2 is a sectional view taken on the line 2—2 of Fig. 1.

45 Fig. 3 is an edge view of one of the feet, and

Fig. 4 is a top or plan view of the same.

Referring to the drawings 1 is a yoke having suspension means 2 by which it can be suspended from a crane, hoist or the like. The

yoke is shown as provided with inclined bearings 3 for a purpose to be presently described. 4 indicates tension rods freely slideable through the yoke and having lugs 5 at their upper ends. 6 indicates vibrators mounted 55 on the upper ends of the rods 4. 7 indicates springs interposed between the lugs and yoke for supporting the rods and opposing transmission of vibration from the rods to the yoke. As shown the springs are seated on the inclined 60 bearings 3 so as to give the rods 4 a tendency to move towards each other at their lower ends. At the lower ends of the rods there are feet 8, and they are shown as claw 65 feet so that the claws 9 may engage the corners of the bottom flask 10. The feet 8 are shown as having upwardly inclined surfaces 11 which engage with downwardly inclined bearing surfaces on the under side of the lugs 12 of the flask 10. The purpose of the inclined 70 bearing surfaces is to insure engagement of the feet with the flask.

The air line for the vibrators is shown at 13, and it includes the end valve 14 and the flexible connections 15. 16 is a means for 75 lubricating the vibrators.

Normally the lower ends of the rods are spaced apart and for use they are swung toward each other under the ends of the bottom flask of the stack. The yoke is then 80 lifted by means of the eye 2 carrying with it the stack of flasks, and when the vibrators are started the flasks are freed from sand but the springs 7 prevent transmission of vibration to the yoke.

It will be obvious to those skilled in the art to which the invention relates that modifications may be made in details of construction and arrangement and matters of mere form without departing from the spirit of 90 the invention which is not limited to such matters or otherwise than the prior art and the appended claims may require.

I claim:

1. A shockless shake-out bail for a stack of 95 flasks comprising a yoke having suspension means, tension rods slideable through the yoke and having lugs, vibrators operatively connected with the rods, springs between the lugs and yoke for supporting the rods and oppos- 100

ing transmission of vibration to the yoke, and feet at the ends of the rods for engaging the bottom flask.

2. A shockless shake-out bail for a stack of flasks comprising a yoke having suspension means, tension rods slideable through the yoke and having lugs, vibrators operatively connected with the rods, springs between the lugs and yoke for supporting the rods and opposing transmission of vibration to the yoke, feet at the ends of the rods for engaging the bottom flask, and air connections on the yoke for the vibrators.
3. A shockless shake-out bail for a stack of flasks comprising a yoke having suspension means and inclined bearings, tension rods freely slideable through the yoke and having lugs, vibrators on the rods, springs between the lugs and inclined bearings, and feet at the ends of the rods having inclined faces for engagement with complemental inclined faces provided on the bottom flask.
4. A shockless shake-out bail for a stack of flasks comprising a yoke having suspension means and inclined bearings, tension rods freely slideable through the yoke and having lugs, vibrators on the rods, springs between the lugs and inclined bearings, and claw feet having inclined faces for engaging inclined faces provided on the bottom flask and also adapted to engage the corners of that flask.

JOHN T. RAMSDEN.
